UNITED STATES PATENT OFFICE.

RALPH D. MATTESON, OF EAGLE, IDAHO.

HUMIDIFIER.

Application filed May 28, 1927. Serial No. 194,957.

This invention relates to improvements in humidifiers, particularly devices of a type for producing humidity in the atmosphere by means of driving a current of air through and around strips of cloth, thereby producing a large humidified area from which the surrounding atmosphere may take up water or other liquid.

An object of this invention is to provide a device in which water or other liquid may be used for supplying moisture to the atmosphere, thereby increasing the humidity and by artificial means maintain the moisture in the air under constant conditions.

15 A further object of this invention is to provide a humidifier which may be easily adapted for use in dwellings, offices, hospitals, schools, churches, factories, cigar cases, storage rooms, or other suitable places, and wherever it is important to maintain a reasonably 20 constant degree of humidity in the atmosphere.

Other objects of this invention will appear from the following detailed description of the 25 device and as disclosed in the two sheets of drawings which are herewith made a part of this application.

In the drawings—

Figure 1 illustrates a front elevational view 30 of the moistener adapted to cooperate with a fan, showing the lower edge of the moistener within a receptacle for receiving the drippings.

Figure 2 represents an elevational view of 35 the humidifier with the moistener element folded in the container for the liquid, arranged at the top of the fan, and also disclosing a receptacle near the base of the fan for receiving the drippings.

40 Figure 3 illustrates a side elevational view of the humidifier disclosing the liquid container, moistener, receptacle for the drippings and the fan, in assembled relationship.

Figure 4 represents a sectional view of the 45 receptacle for the moistener disclosing the moistener in folded relationship therein, when not in use.

The humidifier, as disclosed in this invention, comprises a container 1 for holding water or other liquid which is adapted to be attached to the upper edge of a fan guard 2, as at 3, the fan being preferably of a rotary type, and the liquid container 1 being provided preferably with a hinged top portion 4 50 adapted to open over the fan guard 2 in such a

manner that a wick or moistener element 5 may be extended over the forward longitudinal edge of the liquid container 1 into the container a suitable distance as at 6. The moistening element 5 may be attached along the 55 longitudinal edge of the container 1 by any suitable means such as a clamping element 7 and 8, the element being adapted to be hinged along the front longitudinal edge of the container 1 and the moistening element 5 clamped firmly between the two elements 7 and 8 by means of set screws 9. The liquid container 1 is preferably held firmly in position by means of braces 10 connected to a portion of the fan construction and container 1, the forward portion of the container 1 being held firmly in position by a connection with the fan guard 2. The liquid container 1 and its cover portion 4 is so constructed that when not used as a liquid container it may readily 60 function as a holder for the wick or moistener 5 in folded relationship therein, as clearly disclosed in Figure 4. In order to provide efficient means for opening and closing the cover portion 4, an extended lug section 11 is positioned on the forward part of the cover. Obviously, the wick or moistener element 5 may be extended into the container 1 and clamped into position to any desired amount, thereby 65 controlling the supply of moisture passing through the moistener 5. The water or other liquid is absorbed into the wick portion 5 within the container and thence passes between the clamping elements 7 and 8 into the hanging portions of the moistener element 5 which is adapted to extend across the face of the electric fan portion 12. The lower edge of the moistener or wick portion 5 is adapted to extend into the auxiliary receptacle 13 in which some of the liquid carried down through 70 the wick 5 will collect as at 14.

The rotary fan, to which the container 1 and 4 is attached, may be controlled in the usual manner by variable resistance coils or other devices for controlling the speed of the 75 fan and at the same time maintaining a suitable humidity to the room or other place.

In operation, this invention provides a humidifier comprising substantially a wick or moistener portion, the upper end of which 80 is submerged in liquid, the moisture passing downward through the wick in front of the revolving fan element, the lower edge of the wick being extended into an auxiliary receptacle for receiving the drippings or moisture 85

which may not be expended into the atmosphere.

It is preferred, in this invention, to form the moistener or wick 5 having a series of 5 vertically extending slots cut therein as at 15 and 16, thereby forming a plurality of strips, the strips being preferably twisted so as to give the best possible circulation of air therethrough. The lower or free ends of the strips 10 are preferably clamped between suitable metal holders 17 and when in operation, the metal holder is adapted to enter the auxiliary receptacle 13 and be held in position therein by means of a metal post 17 located within 15 the receptacle 13, thus functioning to hold the wick firmly in place. The container portions 1, 4 and 13 may be made of any suitable material such as copper, or any other non-rust metal.

20 It is to be understood that substitutions and alterations may be made in the disclosure of the device as shown in the different figures of drawings in this application within the scope of the appended claims, without affecting the merits of this invention.

What I claim is:

1. In combination, an air circulating device, a liquid container connected therewith, a wick for absorbing the liquid extending 30 from the container, the wick extending in front of the circulating device, thereby providing means for humidifying the atmosphere, the container for the liquid being fastened to the upper portion of the circulating 35 device and provided with a cover section, adjustable clamping means for the wick hingedly attached to the longitudinal edge portion of the container, the wick comprising a plu-

rality of twisted strips providing a maximum air circulation therebetween.

2. In combination, an air circulating device, a liquid container connected therewith, a wick for absorbing the liquid extending from the container, the wick extending in front of the circulating device, thereby providing means for humidifying the atmosphere, the container for the liquid being fastened to the upper portion of the circulating device and provided with a cover section, adjustable clamping means for the wick hingedly attached to the longitudinal edge portion of the container, the wick comprising a plurality of twisted strips providing a maximum air circulation therebetween, the free lower ends of the strips being suitably 55 clamped together.

3. In combination, an air circulating device, a liquid container connected therewith, a wick for absorbing the liquid extending from the container, the wick extending in front of the circulating device, thereby providing means for humidifying the atmosphere, the container for the liquid being fastened to the upper portion of the circulating device and provided with a cover section, adjustable clamping means for the wick hingedly attached to the longitudinal edge portion of the container, the wick comprising a plurality of twisted strips providing a maximum air circulation therebetween, the free lower ends of the strips being suitably clamped together, and means for receiving the lower free edge of the wick within an auxiliary receptacle.

In testimony whereof I affix my signature.
RALPH D. MATTESEN.
